POWER OPERATED HOSE CLAMP OR THE LIKE

James A. Giese, 1114 Trawek, South Houston, Tex.

Filed Apr. 1, 1964, Ser. No. 79,304

Term of patent 14 years

(Cl. D54—13)

FIG. 1

FIG. 2

FIG. 3

FIG. 1 is a perspective view of a power operated hose clamp or the like having ornamental features of the present invention, FIG. 2 is a reduced back view of the clamp of FIG. 1 showing the clamp rotated 135° from its position in FIG. 1; and FIG. 3 is a top view of the clamp of FIG. 2.

I claim:

The ornamental design for a power operated hose clamp or the like, substantially as shown.
